United States Patent Office

Des. 183,782
Patented Oct. 21, 1958

183,782

TELEVISION RECEIVER

Catherine S. Winkler, Philadelphia, and Richard J. Whipple, Abington, Pa., assignors to Philco Corporation, Philadelphia, Pa., a corporation of Pennsylvania

Application November 19, 1957, Serial No. 48,546

Term of patent 14 years

(Cl. D56—4)

The side of the television receiver not shown is substantially the same in appearance as the side shown.

We claim:

The ornamental design for a television receiver, substantially as shown and described.
